UNITED STATES PATENT OFFICE.

IRA MUNSON, OF WAYNE, MICHIGAN.

WASHING-MACHINE.

SPECIFICATION forming part of Letters Patent No. 259,039, dated June 6, 1882.

Application filed February 17, 1882. (No model.)

To all whom it may concern:

Be it known that I, IRA MUNSON, of Wayne, in the county of Wayne and State of Michigan, have invented new and useful Improvements 5 in Washing-Machines; and I do hereby declare that the following is a full, clear, and exact description thereof, reference being had to the accompanying drawings, which form a part of this specification.

- 10 The nature of this invention relates to certain new and useful improvements in the construction of that class of devices or machines employed for clothes-washing in which a vibrating rubber having angularly-disposed strips is used in connection with a tray also having angularly-disposed strips; and the invention consists in the peculiar construction and combination of parts, as more fully hereinafter described and claimed.
- 15 Figure 1 is a side elevation of the machine, with a portion of the shell broken out to show the interior arrangement of parts. Fig. 2 is a detached view, in perspective, of the vibrating rubber. Fig. 3 is a like view of the removable stationary rubber.

20 In the accompanying drawings, A represents the tub of a machine, rectangular in form, open at top, with a tight bottom and downwardly and inwardly sloping ends. Standards B are secured centrally and one on each side of the tub, and these standards are provided upon their inner faces with vertical channels b, to receive the shaft c of the rotating rubber C. These channels allow of a vertical 25 play of the stationary rubber to enable it automatically to conform its position to the amount or mass of clothes in the tub, and at the same time prevent any lateral motion of said shaft. The rubber C is made of two segments of circles, d, arranged coincident to each 30 other, hung upon the shaft, and upon the periphery of these segments is secured a series of square slats, so laid into the periphery of the segments as to present the corners, as shown in Fig. 2. Handles or arms e are secured to the sides of the segments, eccentric thereto and concentric to the shaft, so that when in a normal condition the handle e' at 35 the end of these arms projects toward one end of the tub. Upon the side of these seg-

ments—adjacent to the position where the arms are secured and projecting slightly beyond the ends of the arms—is secured what may be termed a "retracting-plate," f.

A frame, D, of the form shown in Fig. 3, is 40 constructed to fit inside and rest upon the bottom of the tub A.

Arranged in a circular form, or partially circular, to conform to the periphery of the segments of the rotary rubber, is a series of 45 square slats, set in diamond shape, so as to present the corners of the slats upwardly, and in each end of this frame or stationary and removable rubber are secured two plates, g g', the outer edges of which are cut away in the 50 center slightly, as shown, so as to produce concavities to allow the free passage of water between said plates and the ends of the tub, and yet allow the said frame or tray D to fit tightly at its sides and corners in the tub, to 55 prevent accidental displacement.

In operation, the parts being all in place and the tub being partially filled with water or suds, the clothing to be washed is placed between the stationary and the rotating rubbers, 60 and a rocking motion communicated to the vibrating rubber by means of the handles. In the downward motion of the handle the clothes are pressed between the two rubbers and forced toward the rear of the machine until 65 they strike the plate g in the stationary rubber at that end. The reverse of this motion brings the plate f on the side of the segments into contact with the clothing resting against the plate in the frame and forces such material 70 back to its original position, and these motions are continued, by which a rubbing of the clothes is produced, which, at every reverse motion, are turned over to present a new surface to the 75 next movement.

80 The turning of the clothes is produced by the plates f g, as follows: When the clothes are placed in the machine the downward movement of the handles causes the vibrating rubber to rub the clothes over the angularly-placed ribs 85 of the frame or tray D until they reach the plate g, which, by reason of its right-angle edge presented to the clothes, holds the same, when the reverse movement of the rubber 90 causes its angularly-placed ribs to rub over the 95 clothes.

clothes until the right-angle edge of the plate *f* reaches them, when, as the movement is continued, they are turned over and rubbed again.

I am aware that vibrating rubbers and stationary trays, both having angularly-disposed ribs, are old, and I do not therefore claim such device.

What I claim is—

1. The combination, with the tub A, of the frame or base D, provided with angularly-disposed ribs, the rubber C, provided with similar ribs, and the plates *f* and *g*, secured, respectively, to the rubber C and frame D, and hav-

ing right-angle or square edges next to the angularly-disposed ribs, substantially as and for the purpose specified.

2. In combination with the tub A and the vibrating rubber C, the removable frame or tray D, and the plates *g* *g'* of said frame, having concave outer surfaces, substantially as and for the purpose specified.

IRA MUNSON.
